UNITED STATES PATENT OFFICE.

GOTTLÖB AICHELE, OF NELLINGEN, NEAR ESSLINGEN, GERMANY.

ESCAPEMENT MECHANISM.

Application filed January 23, 1924. Serial No. 687,903.

To all whom it may concern:

Be it known that I, GOTTLÖB AICHELE, a citizen of the State of Württemberg, Germany, residing at Nellingen, near Esslingen, 5 Württemberg, Germany, Kaiserstrasse 2, have invented certain new and useful Improvements in an Escapement Mechanism, of which the following is a specification.

This invention relates to a mechanical movement commonly termed an escapement for use in connection with typewriting machines and intended to produce progressive intermittent motion of the carriage with the platen or paper roller by the forward and 15 backward movement of the type-bars. The means employed for the purpose comprises primarily a divided controlling gear-wheel and a dog or control-knife cooperating with the parts of said wheel; the characteristic features of these parts reside therein that the opposite faces of the teeth of the controlling-wheel halves and of the faces of 20 the dog cooperating with said wheel are oblique, in such a manner, that jerky movements of the cooperating parts are obviated and only sliding motion is obtained. As a 25 result of this, a uniform smooth feed of the carriage is provided and the noise resulting from such jerky motion is obviated. The dog is reciprocated in accordance with the 30 operation of the type-bars and moves from one gear-wheel part to the opposite gear-wheel part in harmony with the movements of the type-bars toward and away from the 35 platen of the paper-carriage.

My invention is illustrated by way of example in the accompanying drawing in which Figure 1 is a vertical section through the escapement showing the combination 40 and arrangement of parts forming the new mechanical movement, some of the parts being shown in side-view, Figure 2 is a front view of the device, partly in vertical section, and Figures 3-8 are diagrammatic illustrations showing, on an enlarged scale, the various positions of the halves of the controlling gear-wheel and of the operating dog relatively to one another, as is all fully described hereinafter.

50 The upright standard a is provided at its upper part with two bearings a^1 and a^2 carrying centres b which support a short horizontal shaft c on which is secured a cog-wheel d meshing with a rack e . The latter

meshes also with a cog-wheel f connected 55 with, or forming part of, a box g enclosing a spiral spring whereby the carriage is propelled in one direction in successive steps.

The shaft c supports the bipartite controlling gear-wheel h , i ; the half h is 60 capable of being rotated on this shaft, but the half i is affixed thereto by a screw k . The wheel-halves h and i are coupled with each other by projections h' and i' , formed on the gear-sections h and i respectively and 65 overlapping each other in spaced relation to form a gap l as shown by dotted lines in Fig. 1. The said halves are so shaped that a space is left, or a chamber is formed between them, in which space or chamber a 70 spiral spring m is located; one end of this spring is connected at the point m' with the wheel-half h , the other at the point m'' with the wheel half i . The spring m exerts a tension whereby the gear sections h and i 75 are progressively rotated in alternate sequence as the mechanism is operated.

The dog n is carried by a double-armed lever o , o^1 made integral with pivots o^3 , o^4 , and supported between centres p , p . The 80 lever-arm o^1 has a slot o^2 in which a slide q^1 , connected with a rod q , may be adjusted and fixed. The dog n is so arranged as to swing upon a pivot n^1 and is subjected to the upward pressure of a bolt n^2 which itself is 85 pressed upwardly by a spiral spring w . The pivotal upward movement of the dog n is, however, limited by an abutment lug n^3 .

The double-armed lever o , o^1 is oscillated 90 by means of the reciprocating rod q which is actuated, for instance, by the control-bridge (not shown) of the typewriting machine. r is a spiral spring which encompasses the pivot o^4 of the lever o , o^1 , and is 95 prevented from leaving its place by a collar o^5 of said pivot o^4 ; the spring r tends constantly to hold said lever in the position shown in Figure 1. An adjusting screw s is located on the arm o of the lever o , o^1 for arresting the throw thereof in one 100 direction.

The upper end of the dog n cooperates alternately with a tooth of the gear wheel section h and with a tooth of the gear-wheel section i . The shape of the teeth of the gear-wheel sections h and i is shown in Figures 3-8 on an enlarged scale, there being shown 105 in each of these figures three teeth of the

wheel-half h and three teeth of the wheel-half i . In the operation of the machine, the dog n is moved alternately from h to i and from i to h , and thus brings about a step by 5 step progression of the bipartite gear $h-i$. An essential feature lies in the shape of the dog and of the teeth, in that the operating end of the dog, i. e. the end cooperating with the teeth of the two wheel halves, is 10 triangular in horizontal cross-section as shown in the Figures 3-8, and the end faces of the gear-wheel halves, i. e. their opposite end-faces lie in transversely arranged planes or are cut off obliquely in opposed relation 15 as shown, for instance, in Figures 4 and 7.

Supposing, a type-bar is being moved toward the paper roller or platen so as to print its character upon the paper running around the roller, the dog n (Fig. 3) which 20 at the time contacts with the tooth x of the gear-wheel half i is moved to the right, along the tooth x , by means of the rod q and the lever o, o' , and at the middle point of its path, is located at the oblique end- 25 face of the tooth x (Fig. 4); from this point the dog n passes over to the tooth y of the gear-wheel half h . As soon as the dog n has left the tooth x , the wheel half i is rotated slightly in the direction indicated 30 by the arrows between the Figures 3 and 4, 4 and 5, 6 and 7, and 7 and 8; this is accomplished by means of the spring m located within the gear-wheel h, i , or between its halves respectively, as already described. 35 The extent of this rotary motion is such that the tooth x , which occupied the position indicated by dotted lines in Fig. 5 when its oblique end-face and the oblique face of the dog n were in registering surface engagement with each other, shifts to the position shown in full lines in Figure 5 in which the dog has reached the end of its movement to the right. The position of the parts shown in Figure 6 is the same as in 40 Figure 5, the only difference being that the dog n is now about to move in the reverse direction, which reverse movement begins when the type bar just used commences to move away from the paper, or the paper- 45 roller respectively, in a return movement toward its positions of rest. The reverse direction is indicated by the horizontal arrow below the designation "Fig. 6." Similar arrows indicating the direction of movement of the dog appear also below the designations "Fig. 3," "Fig. 4," "Fig. 5," "Fig. 7," "Fig. 8." The dog n now move along 50 the tooth y until it arrives at the oblique end-face thereof. While the oblique faces of 55 n and y move along one another, the gear-wheel half h is turned by the spring m in the direction indicated by the vertical arrow (Fig. 7) and the dog contacts finally with the tooth x^1 of the gear-wheel half i . The 60 dog n now glides along this tooth (Fig. 8)

until it arrives in its lefthand end-position, whereupon the succession of operative steps in the direction from the left to the right (Figs. 3-5) is repeated, and so on. At this stage, however, the next tooth of h , viz. y^1 , 70 will cooperate with the dog, and also when the latter repeats its path from the right to the left, the next tooth of i will cooperate therewith, and so on. As the dog n oscillates back and forth the oblique end surfaces of the teeth of the gear sections h and i will successively glide along the inclined faces of the dog in smooth, uniform movements free from jerks; the step by step 75 operation of the escapement is thus devoid 80 of shocks and is accomplished with a minimum of noise.

I claim:

1. A mechanical movement for the production of progressive intermittent movement of the paper-carriage by the to-and-fro movement of the type-bars, comprising, in combination, two co-axial cog-wheels arranged side by side and having teeth with oblique end-faces projecting toward each other and lying in close proximity to one another; a movable dog having a triangular operating end, the opposite active faces of which are parallel to said end-faces and adapted to cooperate alternately with one and the other of said wheels and means for reciprocating said movable dog, substantially as described.

2. In a typewriter, an escapement comprising a plurality of co-axial gears, a movable dog cooperating with said gears to produce a step by step feed thereof, the cooperating surfaces of said dog and the teeth on said gears being correspondingly inclined and arranged to slide along each other during the movement of the dog to provide a gradual rotation of said gears in the feeding steps thereof and means for actuating said dog.

3. In a typewriter, an escapement comprising a pair of coaxial gear wheels in surface parallelism with each other, the teeth of which project toward each other and have their inner end faces in transversely arranged planes, a dog reciprocable in the direction of the common axis of said gear wheels and adapted to pass from one gear wheel to the other, said dog having surfaces slidingly cooperating with said inner end surfaces of said teeth in the passage from one gear wheel to another to permit a gradual rotation of said wheels in successive steps and means for operating said dog.

4. In a typewriter, an escapement comprising a pair of coaxial gear wheels, the teeth of which project toward and beyond each other, the end faces of said teeth being oblique to their length, a dog reciprocable 125 in the direction of the common axis of said

gear wheels and slideable along the teeth of one on to the teeth of the other, said dog having inclined surfaces cooperating with the end faces of said teeth, in the passage 5 from one gear wheel to another to permit gradual rotation of said wheels in successive steps and means for vibrating said dog.

In testimony whereof I affix my signature in presence of two witnesses.
